UNITED STATES PATENT OFFICE.

ALFRED FELLHEIMER, OF NEW YORK, N. Y.

TICKET-SELLER'S CASE.

1,333,610.

Specification of Letters Patent. Patented Mar. 16, 1920.

Application filed September 18, 1918. Serial No. 254,641.

To all whom it may concern:

Be it known that I, ALFRED FELLHEIMER, a citizen of the United States, and a resident of the city of New York, borough of Manhattan, in the county and State of New York, have invented new and Improved Ticket-Sellers' Cases, of which the following is a full, clear, and exact description.

This invention relates to ticket cases and particularly to a case for ticket sellers and has for an object the provision of an improved construction over my co-pending application, Serial No. 196,176, for ticket-seller's booth.

Another object in view is to provide a case in which the tickets are positioned so as to be readily accessible at all times, while means are provided which will indicate the name and character of the various tickets without requiring an examination of the tickets.

A still further object of the invention is to provide a case having inclined pigeon holes for receiving tickets and legend holding means adjacent the end of the pigeon holes whereby the tickets may be positioned in the pigeon holes loosely or in carriers and removed with quick facility when the case is in use.

30 In the accompanying drawing:

Figure 1 is a fragmentary perspective view of part of a case disclosing an embodiment of the invention.

Fig. 2 is a longitudinal vertical section 35 through a case similar to that shown in Fig. 1, the same being on an enlarged scale.

Fig. 3 is a front view of part of the case shown in Fig. 1, the same being on an enlarged scale.

40 Fig. 4 is a detail perspective view of a card retaining and legend holding device embodying certain features of the invention.

Fig. 5 is a view similar to Fig. 2 disclosing a slight modified form of the invention.

45 Fig. 6 is a perspective view of a carrier for holding tickets, same embodying certain features of the invention.

Fig. 7 is a front view of part of a cabinet showing a slightly modified form of the invention.

50 Fig. 8 is a fragmentary sectional view through Fig. 7 on line 8—8.

Fig. 9 is a plan view of a retaining clip for a number of compartments.

55 Referring to the accompanying drawing by numerals 1 indicates a casing which is

provided with a number of pigeon holes 2, said pigeon holes being arranged with inclined bottoms 3. The partition walls 4 between each of the pigeon holes 2 are provided with grooves 5 and 6 arranged at a steeper angle than the bottom so as to accommodate a clip 7 which will act as a stop for the tickets 9 in the various pigeon holes. The clips 7 are provided with a pair of depending arms 8 adapted to fit into opposite grooves 5 and 6 while the body 10 from which these arms extend is bent over for forming a top 11, said top having a spur 12 adapted to snap into the notch 13 as shown in Fig. 2 for locking the clip 7 in place. The top 11 is also provided with a turned over flange 14 and pressed out clamping stops 15 and 16, said flange and said stops accommodating cards 17 on which various legends are provided, as for instance the names of cities. It is of course understood that there is one clip 7 for each of the pigeon holes 2 so as to normally prevent the tickets from accidentally moving out of the 80 pigeon holes.

As shown in Fig. 2 the various bottoms 3 are cut away at 18 so that when the finger or thumb of the operator presses against one of the tickets 9 and then slides the same 85 downwardly said ticket will pass out of the pigeon hole as shown in dotted lines in Fig. 2. Preferably the lower ends of the arms 8 are slightly bent so as to normally prevent the accidental passage of any of the tickets 90 through the cutaway portion 18, though yielding readily when the ticket seller moves the ticket manually. Preferably the spur 12 is used for holding the clip in place, but if desired the arms 8 could be slightly 95 spread or contracted as desired for causing a proper pinching action against the partition walls 4. The clip is preferably made from metal so that the arms 8 and other parts may be moved as just described, but it is evident that the clip could be made from wood or other material and instead of depending on the spur 12 or the resilient arms 8 for holding the clip in place it could be held in place by an adhesive of any kind. 100 When the parts are made of wood an adhesive is used and the end 11 is eliminated. A metal clip of any desired kind is substituted for holding a legend card. The tickets 9 are arranged on end in order to save 105 space and to group as many tickets as near together as possible. This prevents the

ready reading of the names on the tickets so that the various legend cards 17 are desirable and the operator may locate the ticket desired by merely glancing at his case and 5 may remove the proper ticket without looking at the ticket.

In providing a new supply of tickets for the various pigeon holes said new supply may be passed through the pigeon holes 10 from the front after removing the clip 7 if desired, or may be passed into the various pigeon holes from the rear after removing the rear covering wall 20 which is preferably a door. The construction of the case 15 and the clip 7 and associate parts not only permits the use of the loose tickets with a suitable follower 21, but also accommodates the tickets when arranged in a carrier 22 as shown in Fig. 6. This carrier is preferably 20 made from pasteboard and is provided with an opening 23 at the front, slot structures 24 and 25 permitting a ready removal of the ticket from the carrier. The rear of the carrier may be open or closed as desired, 25 but the tickets are slid into the carrier from the rear and a following block 21 supplied for holding the tickets in a proper position and causing the same to feed by gravity toward the front of the carrier. When any 30 of the pigeon holes are empty the carrier 22 may be inserted as shown in Fig. 5 and the tickets are in proper position for being dispensed as described in respect to Figs. 1 and 2. This arrangement of carrier and case for 35 accommodating the same is of an appreciable advantage as the tickets may be packed in the carrier 22 at the printing shop and tied up and sealed at that place. The tickets are left in the carrier from then on 40 until they are used one by one from the case. The wrapping of course must be removed so that the carrier will be as shown in Fig. 6 before it is placed in the case.

Figs. 7 to 9 inclusive show a slightly 45 modified form of the invention especially adapted for use of the carrier 22 as shown in Fig. 6. In this form of the invention the compartments 26 extend from one side of the cabinet or case 32 to the other and are 50 open both at the front and rear. A number of slots 27 are provided in which the division plates may be placed, said division plates being preferably formed of metal, though they may be of other material.

These division plates are used when loose 55 tickets are provided with the cabinet. When the carriers 22 are provided they fill the cabinet from one side to the other and by reason of their size and shape fit against each other and against the front clip 28 which is 60 formed of wood preferably, though it may be formed of other material and secured in place by screws, adhesive, or otherwise as preferred. This clip is provided with a number of openings 29 through which the 65 tickets may be seen. The formation of openings 29 naturally results in the provision of a number of tongues 30 which tongues straddle the grooves 27 or the division plates when they are used. As shown in Fig. 8 a 70 metal clip 31 is provided for receiving a legend card whereby the ticket seller may readily see from this legend card the character of the ticket in that particular compartment. When any carrier 22 is emptied 75 it may be removed from the rear and a new full carrier substituted. As shown in Fig. 8 the bottom 3 of each of the compartments is cut away somewhat at the front to allow the tickets to pass over the clip 31 when 80 moved by the finger of the operator. As shown in Fig. 6 the material of the carrier 22 forming the grooves 24 and 25 will pinch to a certain extent the tickets, said pinching 85 action being assisted by the weight of the tickets and the follower 21 so that the tickets will automatically remain in place until forced therefrom by the thumb or finger of the ticket seller.

What I claim is:

In a ticket case the combination with a carrier having tickets, said carrier having an opening through which the tickets may be removed, of means forming a plurality of inclined compartments open at the top and 95 bottom, each of said compartments being sufficiently wide for accommodating a plurality of carriers, and a clip connected to the case near the lower end of each compartment, each of said clips having a solid section extending across the respective compartments, and a plurality of spaced depending parallel arms for forming windows, said windows being arranged opposite the center of each of the carriers whereby the ticket 100 seller may grasp a ticket from any of said carriers and remove the same.

A. FELLHEIMER.
